(57) **CLAIM**

The ornamental design for a display device, as shown and described.

DESCRIPTION

FIG. 1 is a front perspective view of a display device, shown in an unfolded state;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another front perspective view of the display device, shown in a folded state;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof.

FIG. 15 is a front perspective view of the display device in the unfolded state with a stylus pen that is attachable to and/or detachable from the grooves of the display device according to the first embodiment.

FIG. 16 is a front perspective view of the display device in an unfolded state according to a second embodiment;

FIG. 17 is a front view thereof;

FIG. 18 is a rear view thereof;

FIG. 19 is a left side view thereof;

FIG. 20 is a right side view thereof;

FIG. 21 is a top view thereof; and

FIG. 22 is a bottom view thereof.

(Continued)

FIG. 23 is a front perspective view of the display device in a folded state according to the second embodiment;
 FIG. 24 is a front view thereof;
 FIG. 25 is a rear view thereof;
 FIG. 26 is a left side view thereof;
 FIG. 27 is a right side view thereof;
 FIG. 28 is a top view thereof; and
 FIG. 29 is a bottom view thereof; and,
 FIG. 30 is a front perspective view of the display device in the unfolded state with a stylus pen that is attachable to and/or detachable from the grooves of the display device according to the second embodiment.
 The broken lines shown in the drawings illustrate portions of the display device and form no part of the claimed design.
